UNITED STATES PATENT OFFICE.

PAUL J. McCULLOUGH, OF ST. LOUIS, MISSOURI, ASSIGNOR TO SCULLIN STEEL CO.,
OF ST. LOUIS, MISSOURI, A CORPORATION OF DELAWARE.

LIFTING MAGNET.

Application filed January 15, 1927. Serial No. 161,287.

My invention relates to a lifting magnet, and has for its primary object to produce a magnet in which the magnetic coils may be efficiently and economically secured in place 5 without the use of bolts. Another object of my invention is to provide a novel way of securing the pins associated with the lifting lugs, whereby the magnet is conveniently manipulated.

10 A still further object of my invention is to provide shoes adapted to be shrunk upon such magnets as they are used upon, and which, when they become worn, may be quickly and economically removed and re-15 placed.

With the foregoing and other objects in view, the invention comprises the novel construction, combination and arrangement of parts hereinafter more specifically described 20 and illustrated in the accompanying drawings, wherein is shown the preferred embodiment of the invention. However, it is to be understood that the invention comprehends changes, variations and modifications which 25 come within the scope of the claims hereunto appended.

Fig. I is a top plan view, partly in section, of my improved lifting magnet.

Fig. II is a cross-sectional view of the same. 30 Fig. III is a side elevation, partly in section, of the same.

Fig. IV is an enlarged detail view of one of the lugs and pins whereby said magnet is lifted and manipulated.

35 Fig. V is an enlarged detail sectional view through a portion of one edge of my lifting magnet which is provided with a shoe.

Fig. VI is a detail view showing a modified form of securing in place parts of the 40 magnet.

A designates the main body or core of my magnet, B the lifting lugs by which said magnet is manipulated, C the magnet secured 45 within said magnetic core, D a non-magnetic annular plate for securing the magnet in position in the core A, E an annular peripheral shoe adapted to be shrunk upon the magnetic core at the outer and bottom edge, and 50 F an inner annular shoe adapted to be shrunk

upon the magnetic core at the inner and bottom edge of the plate D.

Near the lower or downward edge of the cavity which contains the magnet C in the magnet core A, I provide grooves 1 which extend inwardly into the magnetic core body. It will be noted by reference to Figs. II and III that similar grooves are formed in the portion designated A' of the magnet core. Similar grooves are formed in the inner and 55 outer edges, respectively, of the non-magnetic plate D. The purpose of these grooves is to provide a seat for Babbitt metal 2, which is poured in around the edges between the non-magnetic plate D and the groove in the 60 magnet core A, whereby said non-magnetic plate D is firmly held in position, and this supports the magnet C. If the shoes E and F are employed, these shoes are shrunk onto the magnet core A after the non-magnetic 65 plates D have been secured in position, as above described. When the shoes are employed, as is usual on the larger sized lifting magnets, they serve also to assist in maintaining the magnet C in position. 70

If the shoes E and F are not employed, as in the type illustrated in Fig. III, that is, the smaller type of lifting magnet, the lower groove in the edges of the non-magnetic plate D is cut as shown in Figs. III and VI, whereby the Babbitt metal 2 forms a slight reinforcing dam, as shown at 3 in Figs. III and VI, thus tending to retain securely the non-magnetic plate D in position. 75

In Fig. IV I have illustrated the pin, and method of fastening the same, which I employ in the lifting lugs B. It will be noted that an opening is provided through the lifting lugs for the receipt of a pin 4. It will be noted that the opening in the righthand lug B (Fig. IV) 80 does not extend the same size through the entire lug but terminates in a smaller opening 5 so as to provide a seat for one end of the pin. In the lefthand lug B (Fig. IV) an opening 6 is formed having a recess 7 therein. 85

The opening 6 and recess 7 are adapted to receive a bent plate 8. The diameter of the bent plate 8 is sufficient to permit it to be inserted in the opening 6, after which it is hammered down flat, as shown in section lines in 90 100

Fig. IV. When so flattened out the plate 8 serves to restrain the pin 4 from being displaced from the openings in the lugs B. When it is desired to remove the pin 4 a tool 5 is inserted in the opening 5 and the pin is driven out, causing the plate 8 to be again bowed outwardly or possibly destroyed, and if a new pin is needed it is inserted in the 10 openings in the lugs B and a new plate 8 inserted to retain said pin in position, as described.

After the magnet C has been placed in position in the magnet core and confined therein by the non-magnetic plate D and held in position either by the Babbitt metal 2 alone or 15 the Babbitt metal and the shoes E and F, the insulating compound shown at G is poured in under heat and pressure, so that all of the interstices between the magnetic core and the 20 magnet are filled with such insulating compound. When the insulating compound has been poured in through the opening 9 in the core A the plug 10 is screwed into such opening, thereby sealing the same.

25 H designates the wires leading to the magnet C.

When it is desired to remove the magnetic coil C from the core A in the structure illustrated in Fig. II, the shoes E and F are removed and then, preferably by a blow-torch, 30 the Babbitt metal 2 is melted and permitted to run out, thus releasing the non-magnetic plate D which permits the magnetic coil C to be removed. It will be noted by Fig. I that 35 the insulating compound G occupies a channel which bears the numeral 11 in Fig. I. It will be noted that this is merely a channel of sufficient diameter to permit the insulating compound G to be freely forced into and around 40 the magnetic coil C.

I claim:

1. In a device of the character described, 45 a core, a magnetic coil positioned in said core and insulated therefrom, a plate for retaining said magnetic coil in said core, and means for retaining said plate in position in said core, said means comprising substantially registering channels on said plate and the interior of said core and a relatively low melting point metal applied to said substantially registering channels whereby said plate is locked in position in said core.

2. In a device of the character described, 55 a core, a magnetic coil positioned in said core and insulated therefrom, a plate for retaining said magnetic coil in said core, and means for retaining said plate in position in said core, said means comprising substantially registering channels on said plate and the interior of said core and metal applied to said substantially registering channels whereby said plate is locked in position in said core.

60 65 3. A lifting magnet comprising, in combination, a body portion, a magnetic coil mounted therein, a plate for maintaining the coil

within the body portion, a groove formed within the body portion, a complementary groove formed within the plate, and an all metal seal fitted within the grooves to serve in retaining the plate in position relatively to the body portion. 70

In testimony that I claim the foregoing I hereunto affix my signature.

PAUL J. McCULLOUGH.
